UNITED STATES PATENT OFFICE.

WILLIAM R. FREEMAN, OF SAN ANTONIO, TEXAS.

PRESSURE-REGULATOR FOR FERMENTED LIQUIDS.

SPECIFICATION forming part of Letters Patent No. 251,428, dated December 27, 1881.

Application filed September 29, 1880. (No model.)

To all whom it may concern:

Be it known that I, WILLIAM R. FREEMAN, of San Antonio, in the county of Bexar and State of Texas, have invented a new and useful Improvement in Pressure-Regulators for Fermented Liquids, of which the following is a specification.

My invention has for its object to provide an improved automatic hydraulic apparatus for supplying compressed air to kegs or casks containing fermented liquids, to replace the vacuum caused by drawing off a portion of the said liquid, and thus to maintain a uniform pressure in such vessels so long as any portion of their contents remains to be drawn therefrom.

The construction and operation of my present invention will be fully understood from the following description with reference to the accompanying drawing, which represents a vertical central section of the said pressure-regulating apparatus connected by an intermediate compressed-air reservoir to an ordinary beer-keg. Air condensed by hydraulic pressure is fed into and stored in a reservoir connected by pipe and check-valve to the keg. When the water-cylinder (the air-compressor) is full a float therein closes the supply-valve and opens the discharge-valve, allowing the water to flow out and air to enter through a vacuum-valve. When the cylinder is thus emptied of water the discharge-valve is closed and the supply opened.

For want of space the upper part of the air compressor and apparatus is shown on the drawing at the upper left side, instead of directly above the lower part, which latter is shown at the right.

A designates the air-compressor—a preferably cylindrical vessel—provided at the top with a vacuum-valve, *a*, and in the interior with a float, *B*. This latter has a vertical opening formed by means of a tube, *b*, through which the valve-rod *C*, common to both supply and discharge valve, is inserted, in order that the said valves may be operated by the rise and fall of the said float as the latter, in its movements, comes in contact with one or the other of two pins or collars, *c c'*, secured on the valve-rod *C* respectively above and below the float. The valve-rod *C* is guided to slide in stuffing-boxes *d e*, arranged respectively in the air-conducting vertical tube *D*, attached to the cover

of the air-compressor *A*, and in the water-conducting tube *E*, attached to the bottom of the air-compressor *A* vertically below and in line with the upper tube, *D*. The stuffing-box *e* secures a water-tight partition in the pipe *E* between supply and discharge valves, the upper portion of the pipe *E* being connected with the discharge-valve by the branch pipe *F*.

His the supply-valve, consisting of a plunger or piston formed or attached upon the rod *C*, and of suitable size to slide water-tight in the bore of the coupling-nipple *c'*, connecting two castings of the pipe *E*.

The seat for the discharge-valve *I* is formed by the upper annular end surface of the discharge-pipe *f*, threaded into the lower end of pipe *E*. The valve *I* is a compound valve, having a central opening, in which is fitted an inner sliding or puppet valve, *I'*, which latter has a central opening, in which the rod *C* slides. The hollow stem of the inner valve, *I'*, extends below the main surface of the valve *I*, and has lateral projections *j* on its lower end to prevent it from getting out of its place. The rod *C*, which fills the hollow valve-stem, is grooved a distance below it, or made cruciform in cross section, thereby forming channels *g*, through which water will discharge when the rod is raised high enough to expose a portion of the said grooves or channels above the valve *I*. The latter remains closed or resting upon its seat *f* until raised by the pin or collar *i* upon the rod *C* as the latter ascends. On the rod again descending the valve may be prevented from accidental suspension by being depressed by the pin or collar *i*, fastened on the rod above the valve. The collar *i* may, however, be dispensed with.

The water entering (as indicated by the arrows 1) gradually fills the cylinder *A* and compresses the air therein. The float *B* rises with the water-surface, and slides upon the yet stationary rod *C* away from the collar *c'* until, by engaging with the upper collar, *c*, it has lifted the rod *C* sufficiently to close the valve *H*, at which instant the collar *i* engages with the under side of the valve *I* and opens the same, whereupon the water is discharged through the pipes *F* and *f*, and the float *B* again descends, and the several parts resume about the position shown in the drawing. In consequence of the vacuum formed in the cylinder *A* on the

descent of the float, the vacuum-valve *a* is kept open by the atmospheric pressure until the cylinder is again filled with air of the same pressure.

- 5 It is evident that when the plunger *H* enters the nipple *e'*, and thus cuts off the water-supply, the float rises no higher to open the discharge-valve *I*; but the plunger *H*, forced by the pressure of the entering water, continues 10 to ascend and to lift the valve *I* farther from its seat until the cylinder *A* has emptied its water through the pipes *F f*, or in direction of the arrows *2*. The whole weight of the float, unsupported by water, then rests upon the 15 lower collar or pin, *c'*, thereby depressing the rod *C* until the supply-valve is again opened and the discharge-valve closed. The upper end, *C'*, of the rod *C* is provided with a weight, *K*, proportioned to a certain pressure upon the 20 valve-piston *H*, said weight, of course, not to exceed the bearing capacity of the float. It is evident that a discharge-valve of excessive area would receive sufficient pressure in direction of arrows *2* (when the plunger *H* had entered 25 the nipple *e'*) to overbalance the pressure in direction of arrows *1*, and thus remain closed, thus rendering the apparatus inoperative. This is, however, prevented, while yet allowing of a liberal discharge area, by the compound valve 30 and channelled rod before described. Before the collar or pin *i'* on the ascending rod *C* strikes the valve *I* the channels *g* should be in position to project their upper ends slightly above the valve, thus allowing water to discharge through 35 the said channels and removing the pressure on the corresponding valve area. As, accordingly, the plunger *H* continues to rise the collar *i'* will strike the lower end of the hollow stem of the inner valve, *I'*, and, raising the latter, relieve the valve of all the pressure due to that area. Finally the collar *i'* will raise the outer ring or annular surface of the valve *I* from its seat. By thus subdividing the valve in two 40 or more parts, successively operated, its area 45 may be made large enough to discharge the water as rapidly as may be desired. The compressed air passes from the cylinder *A*, through pipes *D L*, check-valve *M*, and pipe *N*, to a reservoir, *O*, and from thence (or directly from 50 pipe *N*) through the check-valve *P* and pipe *Q* to the keg or other vessel, *R*, the check-valve *P* preventing any return of the air from the keg *R* to the reservoir *O*, and the check-valve *M* preventing return of air from reservoir *O* to 55 the cylinder *A*, which otherwise would occur when the float descends. The reservoir *O*, charged with compressed air, keeps on replacing the vacuum caused by drawing from the keg *R*, while the cylinder *A* receives fresh air- 60 supplies through its vacuum-valve *a*. To prevent, however, an overpressure of air in the

reservoir and pipes, as might occur when the keg has been left intact for a while, I enlarge the diameter of the upper end, *C'*, of the rod *C* and pack it by a stuffing-box, *T*, fitted in the 65 upper end of a pipe-connection, *S*, above the stuffing-box *d*, and then connect the part *S* by a flexible or other pipe, *U*, to the pipe *L* (or *N*) at some point between the check-valve *M* and the reservoir *O*. By this construction an excess 70 of back-pressure from the reservoir *O*, acting on the enlarged area of the end *C'* of the rod *C*, will raise the latter and close the water-supply valve *H*, thereby preventing any further compression and feed of air in and from the 75 cylinder *A* until the pressure in the reservoir *O* has been reduced by utilizing the air in the keg *R*.

Having thus described my invention, what I claim as new, and desire to secure by Letters 80 Patent, is—

1. In an air or fluid compressor, the supply-valve *H*, adapted to be closed by means substantially as shown, and when closed to act as a piston for opening the discharge-valve by 85 suitable connections between it and the discharge-valve, as and for the purpose specified.

2. The combination, with the vessel *A*, having suitable air-inlet, *a*, and with the pipes *E F G*, of the float *B* and the central rod, *C*, having pins or collars *c c' i'*, and provided with the fast-piston supply-valve *H* and the loose discharge-valve *I*, the said rod working in a watertight packing, *e*, separating supply and discharge valves *H I*, the whole operating together substantially as and for the purpose set forth.

3. The combination, with the common valve-rod *C*, having the fast-piston inlet-valve *H*, and the lifting pin, collar, or shoulder *i'*, of the loose compound discharge-valve *I I'*, composed of successively separable sections of different areas, substantially as and for the purpose set forth.

4. The combination of the compressed-air 105 reservoir *O*, compressing-vessel *A*, and suitable connecting-pipes between the two with the check-valve *M* and pipes *U*, with the connection *S*, the two stuffing-boxes *d T*, the weighted rod *C*, having an enlarged upper end, *C'*, in the box *T*, and the supply-valve *H*, substantially as and for the purpose specified.

5. In an air or fluid compressor, the rod *C* and the compound valve *I*, said valve being composed of sections of different area, and each 110 section opened in succession by the movements of the rod *C*, as and for the purpose specified.

WM. R. FREEMAN.
